US0D1109689S

(12) **United States Design Patent** (10) **Patent No.:** **US D1,109,689 S**
(45) **Date of Patent:** **** Jan. 20, 2026**

(54) **BATTERY CHARGER**

(71) Applicant: **Vector Products, Inc.**, Boca Raton, FL (US)

(72) Inventors: **Ling To Shum**, Boca Raton, FL (US); **Joseph Blaine Cooper**, East Boston, MA (US)

(73) Assignee: **Vector Products, Inc.**, Boca Raton, FL (US)

(**) Term: **15 Years**

(21) Appl. No.: **29/917,430**

(22) Filed: **Nov. 20, 2023**

(51) LOC (15) Cl. **13-02**

(52) U.S. Cl.

USPC **D13/107**

(58) **Field of Classification Search**

USPC D13/103, 104, 105, 106, 107, 108, 109, D13/110, 112, 114, 116, 118, 119, 122, D13/184, 199

(57) **CLAIM**

The ornamental design for a battery charger as shown and described.

DESCRIPTION

FIG. 1 is a top perspective view of an embodiment of the battery charger.

FIG. 2 is a bottom perspective view of the embodiment of the battery charger.

FIG. 3 is a top view of the embodiment of the battery charger.

FIG. 4 is a bottom view of the embodiment of the battery charger.

FIG. 5 is a back side view of the embodiment of the battery charger.

FIG. 6 is a front side view of the embodiment of the battery charger.

FIG. 7 is a right view of the embodiment of the battery charger; and,

FIG. 8 is a left view of the embodiment of the battery charger.

The broken lines shown in the drawings are for the purpose of illustrating boundaries of the battery charger that form no part of the claimed design.

1 Claim, 6 Drawing Sheets
